[57] CLAIM

The ornamental design for a toy construction figure, substantially as shown and described.

DESCRIPTION

FIG. 1 is a perspective view of a toy construction figure showing my new design;

FIG. 2 is a front elevational view thereof;

FIG. 3 is a top plan view thereof;

FIG. 4 is a bottom plan view thereof;

FIG. 5 is a right side elevational view thereof, the side opposite being a mirror image;

FIG. 6 is a rear elevational view thereof; and,

FIG. 7 is a cross-sectional view thereof taken along line VII—VII in FIG. 4.
